No. 737,926.

PATENTED SEPT. 1, 1903.

A. S. HAYDEN & W. F. PACKARD.
IRONING DEVICE FOR SHOEMAKERS.

APPLICATION FILED MAR. 6, 1903.

NO MODEL.

UNITED STATES PATENT OFFICE.

AMOS S. HAYDEN, OF AVON, AND WILLIAM F. PACKARD, OF BROCKTON, MASSACHUSETTS, ASSIGNEES, BY DIRECT AND MESNE ASSIGNMENTS, OF TWO-THIRDS TO FRANK BARTLETT AND LORING G. LITTLEFIELD, OF AVON, MASSACHUSETTS.

IRONING DEVICE FOR SHOEMAKERS.

SPECIFICATION forming part of Letters Patent No. 737,926, dated September 1, 1903.

Application filed March 6, 1903. Serial No. 146,450. (No model.)

To all whom it may concern:

Be it known that we, AMOS S. HAYDEN, residing at Avon, in the county of Norfolk, and WILLIAM F. PACKARD, residing at Brockton, in the county of Plymouth, State of Massachusetts, have invented new and useful Improvements in Ironing Devices for Shoemakers and others, of which the following is a specification.

Our invention consists of an ironing device for shoemakers and others embodying a rotatable wheel having a frictional surface against which the tool or iron proper is placed, so as to be heated by the same without the use of fire, &c., said tool or iron proper being portable and removable from said wheel, so as to be applied to the place of service and returned to said wheel, so as to be reheated.

It also consists of novel details of construction, as will be hereinafter described.

Figure 1 represents a longitudinal section on line $\alpha\alpha$, Fig. 2, of an ironing device embodying our invention. Fig. 2 represents a transverse section thereof on line yy , Fig. 1. Fig. 3 represents an end view of a detached portion. Fig. 4 represents a top view of a detached portion. Fig. 5 represents a top or plan view of the ironing-tool or iron proper.

Similar letters of reference indicate corresponding parts in the figures.

Referring to the drawings, A designates a shaft which is mounted on the standards or bearings B and provided with the pulley C for driving purposes. Bolted or otherwise secured to said shaft is a wheel formed of the heads D, which are placed vertically on said shaft and have their inner sides convex or flaring, so that the space or passage between said heads widens from center to circumference, as at E. On said inner sides of the heads D are facings F, of leather or other material, the same being firmly secured to said sides by rivets or other proper means.

The standards B in the present case are formed with or secured to the trough G, into which the heads D are adapted to rotate, said trough serving as a frame to support the

stands H and J, which are located, respectively, in front and at the rear of said heads D in line with the passage E between the latter. The upper portion of the stand J is bifurcated and has secured thereto the spring-clip K, which rises between the members of the bifurcation, as most plainly shown in Fig. 3.

L designates an ironing device which is adapted more particularly for shoemakers' work, the same consisting of the iron proper or head L' of the form of a tapering-block and connected with the shank M, the latter being provided with handles N.

The operation is as follows: Power is applied to the pulley C, whereby the heads D are rotated, preferably with great speed. The iron is now applied in position in the top portion of the passage E and one handle N rested on the stand H and the opposite portion of the shank M, embraced by the clip K, the iron thus being firmly held and retained in contact with the facings F, whereby owing to the friction between the parts the iron will be heated in a convenient and reliable manner without the employment of fire, an electric current, or other heating medium excepting such as is the resultant friction of the rotary heads on the iron. The iron may then be removed and applied to shoes or other articles to be ironed, burnished, &c., and after rendering service may be returned to the place of location against the heads D and be reheated for further use.

Having thus described our invention, what we claim as new, and desire to secure by Letters Patent, is—

1. A tool-heating device comprising a rotatable head one face of which is oblique to its axis and means connected with the frame of the device for supporting a tool in frictional contact with said oblique face.

2. A tool-heating device comprising a plurality of heads the inner faces of which are separated, means for rotating said heads and means for supporting a tool and retaining it between said faces.

3. A tool-heating device comprising a pair

of heads, the inner faces of which separate from each other toward their peripheries, means for rotating said heads and means for retaining between said faces a tool to be rotated.

4. A tool-heating device comprising a pair of heads the adjacent sides of which flare apart, a facing of friction-producing material on said sides, means for rotating said heads and means for detachably retaining between said facings a tool to be heated.

5. A tool-heating device comprising a pair of heads the adjacent faces of which flare apart, means for rotating said heads and stands adapted to detachably support oppo-

site members of a tool to be heated and to retain the tool-head between said faces.

6. In a tool-heating device, a rotatable head, a shaft carrying the same, a support for said shaft, stands on said support adapted to detachably sustain opposite members of a tool to be heated and retain the tool-head against a face of said rotatable head, and a clip on one of the stands adapted to embrace the adjacent member of the tool. 20

Corrections in Letters Patent No. 737,926.

It is hereby certified that Letters Patent No. 737,926, granted September 1, 1903, upon the application of Amos S. Hayden, of Avon, and William F. Packard, of Brockton, Massachusetts, for an improvement in "Ironing Devices for Shoemakers," was erroneously issued to Amos S. Hayden, William F. Packard, Frank Bartlett, and Loring G. Littlefield, as joint owners of said invention; whereas the patent should have been granted to said *Amos S. Hayden, Frank Bartlett, and Loring G. Littlefield*, they being sole owners of the entire interest as shown by the assignments of record in the Patent Office; and that the said Letters Patent should be read with these corrections therein that the same may conform to the record of the case in the Patent Office.

Signed and sealed this 6th day of October, A. D., 1903.
